UNITED STATES PATENT OFFICE

145,921

DESIGN FOR A SCAPULAR RING OR SIMILAR ARTICLE

Benedict F. Carney, Evanston, Ill., assignor to
Spies Brothers, Inc., Chicago, Ill., a corporation
of Illinois

Application April 23, 1945, Serial No. 119,139

Term of patent 7 years

(Cl. D45—10)

To all whom it may concern:

Be it known that I, Benedict F. Carney, a citizen of the United States, residing at Evanston, in the county of Cook and State of Illinois, have invented a new, original, and ornamental Design for a Scapular Ring or Similar Article, of which the following is a specification, reference being had to the accompanying drawing, forming part thereof.

In the drawing:

Fig. 1 is a perspective view of a scapular ring showing my new design and illustrating the under side of the ring mounting; and

Fig. 2 is a perspective view of the ring illustrating the top of the mounting.

The essential features of my design reside in the recess at the inside of the ring wherein is provided a scapular medal design embodying the image of Mary and the Child and Christ and the Sacred Heart, as shown.

I claim:

The ornamental design for a scapular ring or similar article, substantially as shown and described.

BENEDICT F. CARNEY.
